UNITED STATES PATENT OFFICE.

J. BENNETT WALLACE, OF CHICAGO, ILLINOIS, ASSIGNOR TO GEORGE M. CLARK & COMPANY, OF SAME PLACE.

GENERATING VAPOR-BURNER.

SPECIFICATION forming part of Letters Patent No. 378,120, dated February 21, 1888.

Application filed February 7, 1887. Serial No. 226,786. (No model.)

To all whom it may concern:

Be it known that I, J. BENNETT WALLACE, a citizen of the United States, residing in Chicago, in the county of Cook and State of Illinois, have invented a new and useful Improvement 5 in Generating Vapor-Burners, of which the following is a specification.

This invention relates to the same class of hydrocarbon-vapor-generating burners for 10 gasoline-stoves as that shown in patent to me of March 29, 1885, No. 314,404; and some portions of the invention are designed to improve the construction particularly set forth and claimed in said patent.

15 One object sought in the present invention is to lessen or obviate the disturbance caused by the slight explosions which are continually occurring in that part of the burner where the vaporization takes place, and which 20 are due to the sudden change of particles of gasoline or of foreign matters contained therein into vapor. These explosions, especially in those burners wherein a tube of small diameter is employed as the generating or vaporizing 25 part of the apparatus, affect the flame, and cause a sputtering and unevenness thereof, which is objectionable and disagreeable as well. This 30 evil I overcome by interposing between the generator and the burner a chamber, in which a body of vapor is always present, and in which body the disturbance caused by the explosions will be lost or cushioned, and thus fail to reach or affect the flame.

Another feature of the invention consists in 35 conducting the freshly-formed vapor to the bottom of this chamber and drawing it away from the top thereof, so that the direct communication between the generator and burner, which would be apt to carry the disturbing 40 effect of the explosions to the flame, is broken and opportunity is given the vapor to diffuse itself throughout the chamber instead of proceeding on its way to the burner in an unbroken and continuously-moving current.

45 Other features of the invention relate to the construction of the metal casting in which the gas-chamber and the various passages are formed.

I also employ in my present invention an 50 improved form of deflector, whereby the vapor may be deflected from the induction-tube

of the burner to the under side of the base-plate, in order that the latter and the generator, which is in metallic contact with the burner, may be kept heated when the stove is 55 not in active use. Instead of slotting the induction-tube of the burner and employing a deflector which will move into said tube, and which when not in use forms a part of the 60 wall of the latter, as in my said Patent No. 314,404, I make the tube in two parts—an upper and a lower part—and attach the latter to the deflector, which is hinged to move in a similar manner to the deflector of the previous construction, so that when the deflector is 65 moved into position for operation its lower end takes the position previously occupied by the movable portion of the induction-tube. I also form this movable portion of the induction-tube with a flaring receiving-mouth and 70 a contracted delivery-opening, and separate it from the upper or immovable part of the tube, this latter being also provided with a flaring mouth. It results from this construction that more air is admitted to the burner with the 75 vapor and more perfect combustion produced than with the previous construction and the velocity of the current increased after the well-known principle employed in injectors.

The movable portion of the induction-tube 80 may be appropriately termed the "mixing-tube," and such term will be applied to it throughout the specification.

The generating or vaporizing tube, which is 85 one of small diameter, I now locate above the plane of the base-plate of the burner, and at one side thereof, so that the flame from the burner will envelop it, and thus render it more effective. The vertical feed-pipe, or, as 90 it is termed among the manufacturers, the "stand-pipe," I provide with a valve regulating the admission of the oil, and also at the lower extremity with a trap in which the sediment from the gasoline will collect and from which it may be removed by loosening a screw- 95 plug in the bottom of the trap.

In the accompanying drawings, which form a part of this specification, and in which similar letters of reference indicate like parts, Figure 1 is a front elevation of a burner embodying my present improvements. Fig. 2 is a plan with the base-plate partially broken away.

Fig. 3 is a side elevation, two of the valve-operating wheels shown in Fig. 1 being left off. Figs. 4 and 5 are sections of the deflector, the mixing-tube, the inlet-tube of the burner, 5 and the vapor-feed pipe and its valve, taken upon the line $x x$ of Fig. 3, the movable parts being shown in different positions in the two figures. Fig. 6 is an enlarged vertical section of the lower part of the stand-pipe or feed-tube. Figs. 7, 8, 9, and 10 are sections upon 10 the lines 7 7, 8 8, 9 9, and 10 10, respectively, of Fig. 2. Figs. 11 and 12 show different ways in which the deflector and mixing-tube may be hinged. Fig. 13 is an elevation of the generating and non-generating burners and their 15 connections.

In said drawings, A represents the base-plate, B the cap of the burner, and C is the gasoline feed or stand pipe. The latter is inserted in the under side of a casting, D, formed in one piece with base-plate A, or attached thereto, and opens into a passage, d, in said casting. From this passage a short pipe, e, extends to and connects with one end on the 20 generating or vaporizing tube E, which, as shown, is sufficiently elevated above the base-plate and near the burner to insure its being enveloped or actively impinged upon by the flame from the latter.

From the other end of generator-tube E depends a pipe, e', which extends to the bottom of the cushioning or venting chamber F, formed in said casting D. In this chamber the disturbing effects of the slight explosions due to 25 the vaporizing are dissipated and lost, the body of vapor in said chamber acting as a cushion in absorbing the impulses created by the explosions. All the freshly-formed vapor is first conducted to this chamber, and is drawn from 30 thence to the burner or burners used in the stove. The supply for the generator-burner—*i. e.*, the burner shown in the drawings—may be taken from the bottom of chamber F by the pipe G G', and this is the preferable way, because through this pipe the heavier vapors 35 will more readily find exit, and any unvaporized or impure portions of the gasoline will be thereby drawn away from the chamber; but the vapor to feed the non-generating 40 burner or burners V V' is preferably drawn from the top of the chamber—as, for instance, 45 through passage f f', formed in the casting D and connecting with conduit H, opening into pipe H', leading to one of the burners—or by 50 the pipe i, connecting with pipe J, opening into pipe J', leading to the other of the burners. By thus drawing from the top of the chamber the vapor is compelled to rise through 55 the chamber, and the continuity of the current 60 from generator to burner is thus broken up to some extent. The non-generating burners thus fed are less likely to be affected by the disturbances in the generator than the generator-burner itself, though I have found that, the 65 cushioning-chamber very effectually protects the latter.

Any construction of non-generating burner

or burners may be employed with my cushioning-chamber.

The casting D embodies passage d and chamber F when cast, and the pipes G G' and base-plate may also be cast in one piece therewith. The passages f f' are drilled after casting, as well as the pipes G G'. The generator E and the pipes e e' are secured to the casting by 75 brazing or soldering the latter, while the pipes H, i, and J are united by screw-joints.

In a lateral extension, g, of the pipe G' is located the needle-valve b, controlling the generator-burner. Through this valve the vapor 80 is jetted into the burner induction-tube, the lower portion of which is formed by the short tube K, having a flaring inlet and contracted delivery, and which I call the "mixing-tube," and which registers with the upper portion, 85 L, of the burner induction-tube, shown as passing through the base-plate A. Air is free to enter and mingle with the vapor, both above and below the mixing-tube K, there being an open space between the valve-jet orifice and the mixing-tube, and also between the mixing-tube and the tube L. The mixing-tube is cast 90 with and supported from the hinged deflector M, and when the latter is to be used both are moved to the right, so that the mouth of the 95 deflector registers with the jet-orifice and conducts the vapor to the under side of the base-plate A, where it serves to keep the parts sufficiently heated to enable the stove to be put into active use without delay at any time. 100

The deflector may be hinged to the tube L, as shown in the main figures at m, or the hinge may be located upon the farther side of the tube and mixing-tube, as in Fig. 11, or at top and bottom thereof, as in Fig. 12. The use of 105 this deflector is so fully set forth in my previous patent that I do not now give any extended description thereof. The operating-handle N, which is secured to the deflector, bears with sufficient friction on the pipe G' to 110 hold the deflector and mixing-tube in either position.

O and o are the stems of the needle-valves used in connection with the non-generating burners, and n represents the pan used to contain the igniting-fluid employed when the stove 115 is started.

At the bottom of the stand-pipe is a valve, c, whereby the feed-supply of gasoline is regulated, and below this valve is the chamber P, 120 to which the fluid in the first instance is admitted. This chamber I tap at the bottom and fill the opening with a screw-plug, R, having a central passage, r, and lateral vent s, so that by turning down the plug a short distance the 125 vent is exposed and the contents of the chamber P may be drawn off. As whatever sediment contained in the gasoline is very apt to settle in said chamber P, the plug affords a convenient means for getting rid of the same, 130 the chamber thus acting as a trap and assisting in purifying the gasoline.

I am aware that a large generating-chamber has heretofore been employed in combination

with a comparatively small superheating-chamber receiving the vapor from the first chamber and discharging it to the burner. Such superheating-chamber was, however, in 5 much closer proximity to the flame than the generator itself; but the explosions take place at the point of greatest heat, and hence are much more apt to occur at the superheating-chamber than at the generator in this old construction, and such explosions, not finding vent at that chamber by reason of its contracted character, impart impulses to the current leading from it to the flame and cause the latter to sputter. In my invention I have no superheating-chamber, but subject the fluid to the greatest heat at the generating-tube, in which there 15 is no venting-room wherein the disturbances caused by the explosions may be dissipated, and I locate the venting-chamber between the 20 point of greatest heat and the burner. In my construction, also, all the explosions are taken care of instead of a portion only, as is the case with this old form of stove.

I claim—

- 25 1. In a vapor-stove, a generating-burner consisting of a burner proper, a generator, a cushioning-chamber independent of the generator, a conduit extending from the generator to the cushioning-chamber, and a feed-conduit 30 from said cushioning-chamber to the burner proper, in combination with a non-generating burner and a feed-conduit connecting such non-generating burner with the cushioning-chamber of the generating-burner, substantially as set forth.
- 25 2. In a vapor-stove, a generating-burner consisting of a burner proper, a generator, a cushioning-chamber separate from the generator, a conduit extending from said generator 40 to the bottom of said cushioning-chamber, and a feed-conduit from said chamber to the burner proper, in combination with a non-generating

burner and a feed-conduit from the top of said chamber to said last-named burner, substantially as set forth. 45

3. The combination, in a generating vapor-burner, of the burner-cap B, the plate A under said burner-cap, a casting, D, located at the side of said plate, and the generating-tube E, located above the plane of the plate A and in 50 proximity to the burner B and connected to said casting by feed and discharge pipes e e', substantially as specified.

4. In a vapor-burner, the casting D, in one piece with base-plate A and having chamber 55 F and passage d formed therein, in combination with burner B, plate A, and the generator-tube connecting said chamber and passage, substantially as set forth.

5. In a generating vapor-burner, the combination, with the induction-tube and needle-valve, of the movable mixing-tube K, located between the valve and the induction-tube and at a remove from the latter, so that the air will be admitted to the vapor at the mouth of both 65 tubes when both are in use simultaneously, substantially as specified.

6. In a generating vapor-burner, the combination, with the induction-tube and the needle-valve, of the movable mixing-tube K and 70 70 a deflector-tube, M, substantially as specified.

7. In a generating vapor-burner, the combination, with the induction-tube and needle-valve, of the mixing-tube K and deflector-tube M, the tubes K and M being fastened together 75 and movably hinged to the induction-tube at a remove from the latter, so that when the mixing-tube is in use air will be admitted to both it and the induction-tube, substantially as set forth.

J. BENNETT WALLACE.
